US0D1068738S

(12) **United States Design Patent** (10) **Patent No.:** **US D1,068,738 S**
(45) **Date of Patent:** **** Apr. 1, 2025**

(54) **EARPHONES AND CASE**

(71) Applicant: **Dongguan iglory Co., Ltd.**, Dongguan (CN)

(72) Inventor: **Chensong Li**, Dongguan (CN)

(73) Assignee: **Dongguan iglory Co., Ltd.**, Dongguan (CN)

(**) Term: **15 Years**

(21) Appl. No.: **29/881,312**

(22) Filed: **Dec. 29, 2022**

(30) **Foreign Application Priority Data**

Dec. 1, 2022 (CN) 202230807024.3

(51) **LOC (15) Cl.** **14-01**

(52) **U.S. Cl.**

USPC **D14/223**; D13/108; D3/274

(57) **CLAIM**

The ornamental design for earphones and case as shown and described.

DESCRIPTION

FIG. 1 is a front and top perspective view of earphones and case showing my new design, the case is shown separately for ease of illustration;

FIG. 2 is a rear and bottom perspective view thereof;
FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front and top perspective view of earphones of the earphones and case, shown separately for ease of illustration;

FIG. 10 is a rear and bottom perspective view of the earphones of FIG. 9;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the earphones and case thereof, in an open position; and,

FIG. 18 is a perspective view of a case, of the earphones and case, in a closed position thereof.

The broken lines in the drawings depict portions of the earphones and case that form no part of the claimed design.

1 Claim, 18 Drawing Sheets
